(57) **CLAIM**

The ornamental design for an anti-theft bracket for a foldable gadget, as shown and described.

DESCRIPTION

FIG. 1 is a perspective front view of an anti-theft bracket for a foldable gadget showing the claimed design;

FIG. 2 is a perspective back view thereof;

FIG. 3 is a front view thereof;

FIG. 4 is a back view thereof;

FIG. 5 is a right view thereof;

FIG. 6 is a left view thereof;

FIG. 7 is a top view thereof;

FIG. 8 is a bottom view thereof; and,

FIG. 9 is a perspective back view thereof depicting an exemplary foldable gadget secured therein.

The broken lines in the figures represent portions of the anti-theft bracket and environmental structure that form no part of the claimed design.

1 Claim, 7 Drawing Sheets
